SPACE HEATING RUBBISH INCINERATOR WITH AGITATING MEANS

Louis Davidson, New York, N. Y.

Application December 23, 1944, Serial No. 569,602

1 Claim. (Cl. 126—225)

1
This invention relates to a space heating unit and incinerator and it consists in the constructions, arrangements and combinations herein described and claimed.

It is a particular object of the invention to provide a space heating unit and incinerator which is adapted for use in a fire-place of a home, of a construction enabling the burning of leaves, paper and other burnable waste products, the heat developed thereby passing outwardly into the room for heating thereof.

It is also an object of the invention to provide a space heating unit in which the fuel may be very readily inserted within the unit and securely packed, as well as providing means within the unit, at vertically spaced points, for agitating the fuel to admit air to effect an efficient burning thereof, as well as avoiding the creation of smoke.

It is a still further object of the invention to provide a construction permitting very economical manufacture while still maintaining a unit of sturdy construction, of light weight, enabling ready portability when required.

Additional objects, advantages and features of invention will be apparent from the following description considered in conjunction with the accompanying drawing, wherein

Figure 1 is a top plan view of the unit, with a portion of the top cover broken away.

Figure 2 is a cross section on the line 2—2 of Figure 1.

Figure 3 is a cross section on the line 3—3 of Figure 1.

Figure 4 is a top plan view of a modified form of heating unit with the cover removed.

Figure 5 is a similar view of another form of the device.

Figure 6 is an enlarged detail of the agitator device.

Figure 7 is a schematic view of one of the agitator arms showing the formation of air pockets within the fuel.

There is illustrated a space heating unit and incinerator 10, of substantially rectangular form, consisting of a base 11, side walls 12 and end walls 13. Any approved means for connecting the walls and base may be employed and preferably the unit is supported by legs 14 so as to space the base 11 a distance above the hearth of a fire-place. A closure cover 15 is removably supported upon the upper edges of the walls 12 and 13. The base, walls and the cover of the unit are formed from expanded metal, wire mesh, sheet metal, punched sheet metal, or a combination of these, the perforations 16 permitting circulation

of air within the unit, or ventilation can be accomplished by leaving a gap at spaced points at the juncture of the base and vertical walls as shown, at 16' in Figure 4, and heat conveyed

5 through the thin walls by conduction.

At a point centrally of the base, a support bearing 17 is provided, the cover 15 being formed with a similarly located opening which may be reinforced by a collar 18, and oscillatable within the bearing and the collar there is a shaft 19 which extends above the collar a distance for operative connection of an actuating lever 20. To further support the shaft 19, a strap bar 21 is secured between a pair of walls, positioned adjacent the 10 upper end of the unit, the bar being apertured to permit passage of the shaft therethrough and through the cover.

The shaft 19 is formed with a plurality of vertically spaced transverse openings in each of 20 which there is secured an arm 22—22'. The openings are formed alternately at right angles to each other and the arms will be correspondingly disposed. Inasmuch as the unit is of rectangular shape, the arms 22' are of a length less 15 than the arms 22, but in each instance, the arms stop short of respective side and end walls.

As may be seen in Figure 6, the bearing 17 is formed with an inclined cam face 23 and the lower end of the shaft 19 is formed with a similarly shaped face 24, these faces being complementary to each other, so that upon oscillation of the lever 20 a slight upward movement is imparted to the shaft, and since the arms 22—22' are secured to the shaft, a vertical displacement of 30 fuel is effected, thus creating air pockets within the fuel, in and around said arms through their lengths.

The handle 20 is of considerable length, enabling oscillation of the agitator from a suitable 35 distance from the heating unit, so that the operator need not come into close proximity thereto.

In Figure 4, the shaft 19 is shown as mounted centrally adjacent one of the side walls 12, and with this construction, the arms 22—22' are 40 radially disposed from one side of the circumference of the shaft.

In Figure 5, the bearing 17 is located centrally but in spaced relation to an end wall 13, requiring the arms 22 to be of different lengths.

45 In use, leaves, newspapers and other burnable material is tightly packed in the heating unit through the open top of the device, after which the closure cover is placed upon the unit and the material ignited by placing a lighted match 50 through openings 16 at several points, preferably 55 through openings 16' at several points, preferably

through the base 11. The fuel will readily ignite and in a short while the walls of the unit will become hot, the flame and heat therefrom being radiated into the room. Where the fuel may consist of tightly rolled newspapers or leaves or the like, it may be necessary to provide loosening action in order to release air pockets of the rolled papers and by oscillating the lever 20, a vertical movement is imparted to the shaft 19 and associated arms 22-22'. As may be seen in Figure 7, the arms 22-22' will elevate the fuel slightly throughout the height of the unit, thus releasing air for circulation, and enabling complete combustion of the fuel, and eliminating liability of smoke issuing into the room.

While I have shown and described preferred forms of the device, this is by way of illustration only, and I consider as my own all such modifications in construction as fairly fall within the scope of the appended claim.

I claim:

A space heater and incinerator comprising a housing having thin side walls, a bottom wall and a removable cover, openings being formed in the walls of the housing, an open-ended bearing fixed in the bottom wall, said bearing having an inclined cam face in the base thereof, a shaft journaled in the bearing and the removable cover, means for oscillating the shaft, said shaft having an end face complementary to the cam face of the bearing whereby to impart an up and

10
5

down motion to the shaft under oscillation of the shaft, and said shaft having a plurality of vertically spaced arms extended alternately in right angular relation to the shaft.

LOUIS DAVIDSON.
